UNITED STATES PATENT OFFICE.

ANDREW P. PETERSON, OF DWIGHT, ILLINOIS.

DRILLING-MACHINE.

1,191,993.

Specification of Letters Patent. Patented July 25, 1916.

Application filed January 14, 1916. Serial No. 72,117.

To all whom it may concern:

Be it known that I, ANDREW P. PETERSON, a citizen of the United States, residing at Dwight, in the county of Livingston and 5 State of Illinois, have invented certain new and useful Improvements in Drilling-Machines, of which the following is a specification.

This invention relates to drilling machines 10 and has particular reference to an improved construction of machine for drilling post holes.

The primary object of the invention is to provide a drilling machine of this character 15 which will be light in construction so that the same may be readily transported from one position to another and which may be operated to drill a series of holes of uniform diameter and depth.

Another object of the invention is to provide means whereby holes of a predetermined depth may be drilled.

A further object of the invention is to provide means to cause the drill to clean 25 out the hole it forms without removing the same from the hole.

With the foregoing and other objects in view, the invention consists in the novel features of construction, combination and 30 arrangement of parts, as will be hereinafter more fully described, illustrated in the accompanying drawings, and claimed.

In the drawings:—Figure 1 is a vertical sectional view through the frame of the machine, showing the operating parts thereof in elevation. Fig. 2 is a top plan. Fig. 3 is a vertical sectional view through the drill power shaft and stop means. Fig. 4 is a sectional view on the line 4—4 of Fig. 3. 40 Fig. 5 is a detailed vertical sectional view of the stop mechanism; and Fig. 6 is an end elevation of the drill power shaft.

Referring to the drawings by numerals wherein is illustrated the preferred embodiment of my invention, 1 designates a suitable support for the drill which may be of any desired character, such as a wheeled body or the like, for supporting the frame of the drill in spaced relation from the 45 ground.

The frame of the machine comprises longitudinally extending side bars 2, end bars 3, and transverse connecting bars 4. This frame is substantially rectangular in shape 50 and is elongated to support the various parts of the operating portions of the machine.

Bearings 5 are arranged above the frame 2 and are supported from the frame by means of suitable brackets or connecting elements 6. Arranged within these bearings 5 are shafts 7 and 8, the shaft 7 being provided upon its upper end with a sprocket 9 which is connected with a sprocket 10 upon the upper end of the shaft 8 by means of a chain 11. This shaft 7 near its lower end is 65 passed through a second bearing 12 and has mounted thereon a beveled gear 13 which meshes with a second beveled gear 14 upon the inner end of a power shaft 15 which is supported in a bearing 16 secured to any 70 suitable portion of the frame. The outer end of the shaft 15 is provided with a pulley 17 about which a belt may be arranged from any suitable source of power to rotate the shaft 15, beveled gears 14 and 13, shaft 7, 75 and through the medium of the sprockets and chain, thus rotate the shaft 8. If desired, a suitable crank mechanism (not shown) may be applied to the shaft 15 in order to provide for the manual operation of 80 the drill.

A bearing member 18 is mounted upon the frame of the machine by means of transverse bars 19 and this bearing member is adapted to receive the lower end of the shaft 8 to support the same, a collar 20 being mounted upon the shaft and engaging with the upper face of the bearing 18 to limit downward movement of the shaft into the bearing and thus hold the sprockets 9 and 10 in alinement. The shaft 8 is provided throughout a major portion of its length with a polygonal bore 21 within which is arranged a polygonally shaped rod 22, this arrangement serving to permit of longitudinal movement of the rod 22 relative to the shaft 8 but prevent their relative turning movement. The lower end of the rod 22 has mounted thereon a chuck 23 with which a drill 24 of any desired size or construction 100 may be engaged.

An opening is formed in one side of the bearing 18 and this opening has arranged therein a pin 25, the said pin being adapted to extend into the bore of the bearing with 105 which the shaft 8 is engaged and be received by any one of a plurality of spaced annular recesses 26 in the rod 22. The outer end of this pin 25 passes through an opening in a guide bracket 27 and is connected 110 with a lever 28 by means of a rod 29, the lever 28 being mounted upon a segment 30

- secured to any suitable portion of the frame and having a dog for engagement with teeth upon the segment to lock the pin 25 in any adjusted position relative to the rod 22.
- 5 In operation the machine is placed in a position with the drill 24 over the point where a hole is desired to be drilled. Power is then applied to the pulley 17, which through the beveled gears and sprockets, is transmitted to the shaft 8, which in turn by reason of its peculiar engagement with the rod 22 rotates the rod and drill 24. Before the drill 24 is initially started to cut into the ground, the lever 28 is swung to draw the pin 25 from engagement with the rod 22 so that the combined weight of the drill chuck and rod 22 will function to cause the drill to bite into the ground and begin cutting thereinto. After the drill has cut into the ground a desired distance, the lever 28 is released and the pin 25 under the action of a spring 31 will ride into engagement with one of the grooves 26 in the rod 22. This will prevent further downward movement of the drill, and consequently its cutting operation will be stopped so that as it still rotates it will operate to clean out the earth from the hole it has cut.
- By the provision of a plurality of grooves 26 in the rod 22 it will be noted that after the drill 24 has commenced its cutting operation, the lever 28 may be released to permit of the pin 25 engaging with the rod 22 so that as the said rod moves downwardly and one of the grooves 26 becomes alined with the pin 25, the said pin will spring thereinto and prevent further downward movement

of the drill. It will thus be seen that series of holes of uniform depth may be drilled, the spacing of the grooves upon the rod 22 providing means whereby holes of various uniform depths may be drilled, as will be understood.

From the foregoing description taken in connection with the accompanying drawings, it is thought that the construction and operation of my improved drilling machine will be readily understood and while I have herein shown and described one preferred embodiment of my invention, I do not wish to be limited thereto except for such limitations as the claim may impart.

I claim:

A drilling machine comprising a stationary frame, a shaft rotatably mounted in said frame, means for rotating said shaft, a guide member for said shaft, a rod movable longitudinally within said shaft and adapted for rotation within the latter, said rod having reduced portions, a longitudinally movable locking pin, guiding means for said pin, means for resiliently retaining said pin in operative position with one end engaged with one of the reduced portions of said rod, a lever pivoted upon said frame for withdrawing said locking pin to inoperative position, a locking segment for said lever mounted upon said stationary frame whereby the locking pin may be held in inoperative position, a drilling member, and means for connecting said drilling member with said rod.

ANDREW P. PETERSON.
